LIGHTING FIXTURE WITH ADJUSTABLE LIGHT SHIELDS

Filed Feb. 28, 1950

Fig. 1.

UNITED STATES PATENT OFFICE

2,587,423

LIGHTING FIXTURE WITH ADJUSTABLE
LIGHT SHIELDS

Philip Young, Brooklyn, N. Y., assignor to Neo-Ray Products, Inc., New York, N. Y., a corporation of New York

Application February 28, 1950, Serial No. 146,661

2 Claims. (Cl. 240—78)

1

This invention relates to a lighting fixture for projecting light rays throughout a limited area.

An object of the invention is to provide a lighting fixture which is constructed and arranged to eliminate glare and to direct the light rays downwardly in an intensified beam throughout a limited area.

Another object of the invention is to provide a lighting fixture in which the light beam spread is directed downwardly in the shape of a cone from the center of the light.

Another object of the invention is to provide a lighting fixture including a housing for the light and an element removably mounted in the open lower end of the housing for confining and directing the light rays downwardly throughout a limited area.

With the foregoing and other objects in view, reference is now made to the following specification and accompanying drawings in which the preferred embodiment of the invention is illustrated.

Fig. 1 is a vertical sectional view through a lighting fixture constructed in accordance with the invention and illustrating the same mounted in position in a ceiling.

Fig. 2 is an underside view thereof.

Referring to the drawings by characters of reference, the lighting fixture includes a cylindrical housing 10 which is adapted to be secured in fixed position in a ceiling structure indicated generally by the reference character C with the open lower end 11 of the housing disposed flush with the ceiling line D. Secured to a plaster ring 12 in the ceiling structure is an angulated ring 13 through which the housing slidably protrudes and to which it is affixed by screws 14 extending through circumferentially spaced vertically arranged slots 15 in the housing with the ends of the screws anchored in said ring. The slots 15 permit of vertical adjustment of the housing for disposing the lower end thereof flush with the ceiling line D.

The housing 10 is formed with a top wall 17 to which a lamp socket 18 is secured for supporting a lamp 19 in depending relation within the housing 10. In order to confine the light beam spread from the lamp 19 to a limited area located vertically below the fixture, a removable shield 20 is provided which is adapted to slidably and resiliently fit within the lower end of the housing. The shield 20 is of cylindrical formation consisting of a peripheral wall 21 and a plurality of transversely extending walls which are centrally apertured to allow the light rays from the lamp to be directed downwardly therethrough in the

form of a cone. In the embodiment illustrated, four transverse walls are provided, namely a top wall 22, a lower wall 23 and two intermediate walls 24 and 25 which walls are substantially equally spaced apart and are provided with central openings 26, 27, 28 and 29 respectively which progressively increase in size from the opening 26 in the uppermost wall to the opening 27 in the lower wall so as to provide a frusto-conical central opening in the shield 20 with the center of the light being located at the apex of a cone formed as a continuation of the frustoconical opening as indicated in broken lines E in Fig. 1 of the drawings.

15 The lower wall 23 is secured to the lower end of the peripheral wall 21 and extends outwardly therebeyond so as to cover the lower end of the housing 10 and plaster ring 12 and to extend a short distance over the ceiling line D to thereby provide a finished lower face for the lighting fixture. The shield 20 is adapted to be removed from the housing 10 in order to clean the fixture and to gain access to the lamp 19 for replacing the same. For this purpose, the peripheral wall 21 is provided with circumferentially spaced vertically arranged bowed springs 31 which are riveted or otherwise secured at their upper ends to the outer face of the peripheral wall 21 and with the lower ends of said springs free. The 20 said springs are adapted to resiliently engage against the inner periphery of the housing 10 to frictionally retain the shield in position within the housing.

25 Constructed in this manner, there is provided a lighting fixture which is adapted to be installed in a ceiling structure for directing the light rays from the lamp downwardly through the fixture in the form of a cone with the illuminating element in the lamp located at the apex 30 of the cone. This provides a limited spread of the light rays in the form of a spot light with a clearly defined or sharp outer edge surrounding the spot light.

35 What is claimed is:

40 1. In a lighting fixture, a housing having an open end, a light socket carried by said housing for supporting a lamp adjacent the other end of the housing, a tubular shield removably secured in said housing and extending inwardly from said open end, said shield having a plurality of spaced transversely extending walls formed with central 45 openings, the openings in said walls progressively decreasing in size from the outer wall located at said open end to the innermost wall of said shield 50 to thereby provide a frusto-conical opening in

said shield to permit of light rays from the lamp being directed therethrough in the form of a cone with the apex of the cone located at the center of the lamp, and the outer wall of said shield having its outer peripheral portion extending outwardly in covering relation with the housing at said open end, and a plurality of circumferentially spaced spring clips carried by said shield and adapted to engage the housing for securing the shield in position therein.

2. In a lighting fixture, a housing having an open end, a light socket carried by said housing for supporting a lamp adjacent the other end of the housing, a shield removably secured in the lower end of said housing, said shield comprising an annular wall and a plurality of spaced apertured walls secured to and extending transversely of the annular wall, the apertures in said walls progressively decreasing in size from the outer wall located at said open end to the innermost wall of said shield to thereby provide a frustoconical opening within said annular wall to per-

mit of light rays from the lamp being directed therethrough in the form of a cone with the apex of the cone located at the lamp, and a plurality of circumferentially spaced spring clips carried by said annular wall and adapted to engage the housing for securing the shield in position therein.

PHILIP YOUNG.
